UNITED STATES PATENT OFFICE.

SAMUEL J. TAYLOR, OF GRANTS PASS, OREGON.

REVOLVING WINDOW OR SASH.

Application filed April 6, 1928. Serial No. 267,923.

My present invention has reference to a window construction, and my object is the provision of a semi-circular window having arranged for turning therein a circular sash, 5 whereby the said sash may be turned to open part or all of the window casing.

A further object is the provision of a window construction which includes a casing having a semi-circular upper portion 10 and a pocket depending from said upper portion, a circular sash mounted in the casing for turning therein, together with means for exerting a frictional engagement against the sash to prevent the free turning thereof, 15 means for turning the sash and means for locking the sash to the casing when in closed position.

The invention will be fully and comprehensively understood from a consideration 20 of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the 25 invention nor exceed the scope thereof as expressed in the appended claim.

In the drawings:

Figure 1 is a front elevation of my improvement with parts broken away and 30 parts in section.

Figure 2 is a view of a modification.

Figure 3 is a sectional view on the line 3—3 of Figure 2.

Figure 4 is a view similar to Figure 1 but 40 illustrating a modification.

Figure 5 is an enlarged sectional view on the line 4—4 of Figure 4.

Figure 6 is a detail sectional view on the line 6—6 of Figure 4.

Figure 7 is an elevation illustrating a further modification.

Referring now to the drawings and to Figure 1 in particular, a window frame is broadly indicated by the numeral 1. This 50 frame has an upper semi-circular portion 2 and a lower substantially rectangular portion 3, the latter affording a pocket. The trim for the circular portion of the casing is indicated in Figures 1 and 2 by the numeral 4, the sill by the numeral 5 and the stool by the numeral 6. Of course, the

pocket is covered when the frame is set in a building and likewise, of course, the semi-circular top portion of the frame is arranged in an opening through the building.

The semi-circular portion of the frame is provided with inner and outer semi-circular strips 7, respectively, and between these strips there is arranged the cylindrical sash frame 8. In the showing of Figure 1 the sash frame 8 is centrally divided by a strip 9, and between this strip and one-half of the frame there is a transparent plate 10 and also between this strip and the second half of the frame there is a mesh 11. The inner 70 side members provided by the pocket 3 of the frame 1 have fixed thereon brackets 12 for frictional wheels 13 that contact with the periphery of the sash frame 8. The sash frame is provided with an operating 75 element 14. There are, of course, suitable latching means between the sash frame and the cylindrical portion of the window frame or its casing 4. The friction wheels 13 effectively support the sash frame in the 80 casing, and it will be apparent that by grasping the element 14 the frame can be turned to bring either its transparent face 10 or its mesh face 11 into or partly into the semi-circular portion of the frame. By 85 this means both light and ventilation may be obtained to a room in which the device is arranged and also by this arrangement the entrance of insects to the room is prevented.

In Figures 3 and 4 the pocket of the frame 90 is indicated by the numeral 15 and the semi-circular top thereof by the numeral 16. The window sill is indicated by the numeral 17, and the trim by the numeral 18. Of course, the trim is only arranged around the semi-circular top of the window frame and the lower portion of the frame provides a pocket. In this instance the sill 17 is provided with one or more brackets 19 for a pivot 20 that pass through the lower or straight rail 23 of the semi-circular sash carrying frame 24. Also in this instance the operating element 95 for the sash 24 is revoluble and actuates a toothed wheel 25 to bring a spring influenced dog or latch 26 out of a keeper in the window frame. The sash frame it should be stated is held from side movement by inner and outer arched strips 27 arranged in the arched portion of the window frame. It will be obvious that by turning the operating element 28 the bolt or latch will be brought out of its keeper, which permits of 105 110

the sash being turned in the window frame or casing so that the sash may partly or wholly uncover the upper portion of the window casing.

5 In Figures 4, 5 and 6 there is illustrated a still further modification. In this instance the upper portion of the window frame or casing is indicated by the numeral 29, and the lower portion or pocket therefor by the 10 numeral 30. Fixed in this pocket there are brackets that have journaled thereon friction wheels 31 and 32, respectively. The circular sash carrying frame travels between stirps 33 in the arched portion of the frame 15 or casing 29 and in this instance the frame proper is indicated by the numeral 34 and is of semi-cylindrical formation, but is either surrounded by a curved track or has its ends fixedly secured to such a track. The track 20 is indicated for distinction by the numeral 35 and by reference to the drawings it will be seen that the central portion of the track is arched. This is for the reception of an operating cord or cable 36, and the said cable being 25 wound around the grooved friction wheel 32. Also in this instance the friction wheel 32 has secured in its hub a shaft 37 that has an outer removable operating handle 38. Obviously by turning the handle 38 the sash 34 30 may be turned to bring its glass to cover the opening in the semicircular or arched portion of the window casing or to uncover or partly uncover this opening. Also by this 35 construction the friction wheels prevent the free turning of the sash. Also, obviously the sash may be centrally pivoted, as disclosed by Figures 2 and 3 and latching means between the sash and casing may be provided.

40 In Figure 7 I have shown two sash structures similar to that disclosed by Figures 4 and 5. These sash members are indicated for distinction by the numerals 39 and 40 and are each provided with semi-circular 45 track extensions 41 and 42, which are centrally depressed or grooved. The outer periphery of each of the sashes is likewise de-

pressed or grooved. The lower periphery of the tracks and the sashes 39 and 40 are contacted by friction wheels. The outer friction wheels are indicated for distinction by the numerals 44 and 45 and the inner friction wheels by the numerals 46 and 47. These friction wheels have peripheral grooves, and there is trained around the said 50 wheels and trained through the grooves in the tracks and in the sashes an endless operating cable 48. This cable is wound around the groove in the friction wheel 45 and the said friction wheel has its shaft 49 55 provided with a removable operating handle 50. By turning the handle both of the shafts will be turned in unison.

Obviously the tracks attached to the sashes and forming parts thereof provide, with the 60 sashes substantially circular members and will be so referred to in the appended claim.

The construction of my improved window and operating means therefor will, it is thought, be understood and appreciated by 70 those skilled in the art to which the invention relates so that further detailed description will not be required.

Having described the invention, I claim: 75
A window construction comprising a casing having a semi-cylindrical opening through the upper portion thereof and a pocket below said opening, a semi-cylindrical sash arranged in the casing, means in the casing for preventing the lateral movement of the sash therein, a semi-cylindrical grooved track secured to and extending from the ends of the sash, brackets on the side walls provided by the pockets, grooved anti-frictional wheels journaled in the brackets 80 and contacting with the periphery of the sash or with the track, an operating cable wound around the sash, track and one of the friction wheels, and an operating handle 85 removably secured to the sash of the said friction wheel.

90 In testimony whereof I affix my signature.

SAMUEL J. TAYLOR.
